HER ATTORNEY

UNITED STATES PATENT OFFICE.

ANNA C. MILLER, OF KANSAS CITY, MISSOURI, ASSIGNOR OF ONE-FOURTH TO FRANK J. SCHADEL, OF KANSAS CITY, MISSOURI.

WELL-DRILL.

1,244,882.

Specification of Letters Patent. Patented Oct. 30, 1917.

Application filed February 15, 1917. Serial No. 148,864.

To all whom it may concern:

Be it known that I, ANNA C. MILLER, a citizen of the United States, residing at Kansas City, in the county of Jackson and 5 State of Missouri, have invented a certain new and useful Improvement in Well-Drills, of which the following is a specification.

My invention relates to improvements in well drills.

10 The object of my invention is to provide a well drill which does not require to be removed during the drilling operation for the removal of the cuttings produced by the drill bit.

15 My invention further provides a drill bit having a longitudinal discharge passage in which is located an upwardly opening check valve, whereby the cuttings may be continuously discharged upwardly through the bit 20 and held by the check valve from falling back.

The novel features of my invention are hereinafter fully described and claimed.

In the accompanying drawing, which 25 illustrates the preferred embodiment of my invention, Figure 1 is a view partly in vertical section, partly broken away and partly in elevation of my improvement as applied to a vertically reciprocative rotatable well 30 drill.

Fig. 2 is a vertical sectional view on the line 2—2 of Fig. 1.

Fig. 3 is a bottom view of the bit.

Similar reference characters designate 35 similar parts in the different views.

1 designates the body of my improved bit, the lower portion of the bit being S-shaped in cross section, the arms of the S forming longitudinal blades 2, which are provided 40 each with a longitudinal cutting edge 3, by which, when the bit is rotated, cuts the earth to form a round hole. The arms or blades 2, with the body form two longitudinal channels 4 at opposite sides respectively 45 of the body.

The upper part of the body 1 is provided with a central longitudinal discharge passage 5 having two branches 6 which respectively communicate with the upper ends of 50 the channels 4.

The upper end of the passage 5 forms a valve seat 7 in which is seated an upwardly opening check valve, preferably comprising a ball 8.

55 9 designates a tubular shaft having a

screw threaded lower end fitted to the screw threaded upper end of the bit 1. The shaft is preferably composed of tubing having a laterally turned upper discharge end 10 disposed above the surface of the ground. 60

To the upper end of the tubing 9 is attached the lower end of a bar 11 to which is attached any ordinary type of mechanism, not shown, adapted to vertically reciprocate the drill and to permit axial rotation thereof. 65

As shown in Fig. 1, the body 1 preferably tapers upwardly at two opposite sides to keep the bit from wedging in the hole.

In the operation of my invention, when the bit 1 and shaft 9 are dropped, the lower 70 edge of the S-shaped body, which is a cutting edge will cut into the rock or earth, and the cuttings will enter the channels 4. If water be now poured into the well at the outer side of the shaft 9, it will force the 75 cuttings upwardly through the channels 4, branches 6 and passage 5 past the valve 8 and into the tubing 9. The ball valve 8 is smaller in diameter than the inner diameter of the tubing 9, so that the dirt and water 80 will readily pass the valve. The latter, on the downward movement of the bit will be raised by the water and cuttings, and will seat itself on the upward movement of the bit, thus preventing the dirt which has 85 passed above the valve 8 from falling downwardly past the valve.

The valve is made, preferably, of hardened steel or other suitable material which is heavier than the rock or dirt which is being drilled. 90

The bit 1 and tubing 9 are given an axial turning movement at every downward movement of the bit. The lower sharpened edge of the bit will thus cut a round hole, and 95 the cuttings collecting in the hole made by the bit will cut by the blades 2 and will enter the channels 4, and, as already described, the cuttings will then be forced upwardly, by water poured into the well, through the 100 passage 5, past the valve 8, through the tubing 9 and will be discharged therefrom upon the surface of the ground together with the water which has entered the tubing 9 with the cuttings. As shown in the 105 drawing, the body 1 of the bit tapers upwardly, and the cutting edges 3 of the blades are disposed nearer to the longitudinal axis of the bit than is the periphery of the bit at its greatest diameter. It will be 110

noted further that the channels 4 are open laterally their full length, and also that the lower ends of the branches 6 are downwardly flaring and respectively merge into the upper ends of the channels 4. By means of this construction, the water poured into the well will not be obstructed by the bit at any point, and as the channels are open laterally their full length and merge into the flaring lower end of the branches, the incoming water will have great force in forcing the material cut by the blades through the channels and into the flaring lower ends of the branches 6.

15 I do not limit my invention to the structure shown and described, as modifications, within the scope of the appended claims, may be made without departing from the spirit of my invention.

20 What I claim is:—

1. In a well drill, a bit having an upwardly tapering body provided with a longitudinal blade having a longitudinal cutting edge, the blade forming with the body a longitudinal channel which is open laterally its full length, the body having a longitudinal discharge hole, the lower end of which is flaring and merges into said channel, the body having in said hole a valve seat, and an upwardly opening check valve in said seat.
2. In a well drill, a bit having a lower portion S-shaped in cross section, the arms of the S being longitudinal blades having longitudinal cutting edges and forming with the body two parallel longitudinal channels which are open laterally their full length, the

bit having a longitudinal discharge hole, the lower end of which is flaring and merges into one of said channels, the bit in said hole having a valve seat, and an upwardly opening check valve in said seat.

3. In a well drill, a bit having an upwardly tapering body provided in its upper end with a central longitudinal discharge hole and a valve seat in said hole, the lower end of said hole having two branches provided with downwardly flaring lower ends, the bit having a lower portion S-shaped in cross section, the arms of the S being longitudinal blades which with the body form two longitudinal channels which are open laterally their full length and which at their upper ends respectively merge into the flaring lower ends of said branches, and an upwardly opening check valve in said seat.

4. In a well drill, a bit having a lower portion S-shaped in cross section, the arms of the S being longitudinal blades having longitudinal cutting edges, the cutting edges being located nearer to the axis of the bit than the greatest diameter of the bit, the blades forming with the body two longitudinal channels which are open laterally their whole length, the bit being provided in its upper portion with a longitudinal discharge hole having a downwardly flaring end which merges into one of said channels, the bit being provided in said hole with a valve seat, and an upwardly opening check valve in said seat.

In testimony whereof I have signed my name to this specification.

ANNA C. MILLER.
